DE 4415939 C1 1/1996
(Continued)*Primary Examiner* — Susan E Krakower*(74) Attorney, Agent, or Firm* — Armstrong Teasdale LLP(57) **CLAIM**

The ornamental design for a nipple shield, as shown and described.

DESCRIPTION

FIG. 1 is a perspective of my new nipple shield;

FIG. 2 is a front elevation thereof;

FIG. 3 is a rear elevation thereof;

FIG. 4 is a right side elevation thereof;

FIG. 5 is a left side elevation thereof;

FIG. 6 is a top plan view thereof; and,

FIG. 7 is a bottom plan view thereof.

The broken lines showing nineteen (19) circular elements on the top surface of the nipple shield illustrate environmental structure and form no part of the claimed design.
